COMBINED LAMP SHADE AND MIRROR

Aime Trudeau, 227 NE. 26th St., Miami, Fla. 33127

Filed Jan. 14, 1970, Ser. No. 20,921

Term of patent 14 years

Int. Cl. D26—06

U.S. Cl. D48—16

FIG. 1 is a front perspective view of a combined lamp shade and mirror embodying my new design as seen from above;

FIG. 2 is a rear perspective view thereof as seen from below; and

FIG. 3 is a bottom view thereof on a reduced scale.

I claim:

The ornamental design for a combined lamp shade and mirror, as shown and described.
